UNITED STATES PATENT OFFICE.

ROBERT C. ISAKSEN, OF FLUSHING, NEW YORK, ASSIGNOR, BY MESNE ASSIGNMENTS, TO ADDRESSOGRAPH COMPANY, OF CHICAGO, ILLINOIS, A CORPORATION OF DELAWARE.

PRINTING-PLATE BLANK AND METHOD OF MAKING.

Application filed August 2, 1926. Serial No. 126,443.

This invention relates to the manufacture of printing plates for use in addressing machines and the like and its object is to enable a plurality of plate blanks to be made in one operation and handled as a group, to provide increased production and to reduce the cost of manufacture.

In the accompanying drawings illustrating the invention:

10 Fig. 1 is a plan view of a metal strip.

Fig. 2 shows the strip cut into several plate blanks and also shows the group of blanks as cut moved from cutting to distributing position.

15 Fig. 3 is a perspective view of a single plate blank.

These printing plate blanks are adapted to have printing characters embossed thereon and it has been customary heretofore to 20 make the blanks singly, which requires a separate operation for each blank and individual handling thereof. My invention provides means whereby a plurality of blanks may be cut from a single strip and 25 then moved as a group away from cutting position to a position where they may be distributed, whereby a plurality of blanks, instead of a single blank, may be produced in each cutting operation.

30 I have selected for illustration a strip 4 from which five blanks 5 of a convenient size may be cut. This strip is placed in a machine which is properly supplied with cutting dies for separating the strip into 35 plates and the invention consists primarily in cutting the strip along irregular lines to produce interlocking projections 6 in the edges of adjacent blanks so that after the strip is cut the blanks will be interlocked 40 and remain in group formation against displacement in the plane of the blanks so that the group of blanks may be moved away from cutting position, indicated at the left in Fig. 2, to distributing position, indicated

45 at the right in Fig. 2, without disconnecting or disassembling the several blanks. When the blanks are moved to distributing position they may be arranged over hoppers or other receptacles in which the blanks may 50 be deposited by gravity, or they may be arranged in position to be disconnected by ap-

plying pressure upon the face thereof and distributed in stacks, or they may be separated and distributed in any other desired manner. It will be understood that to disconnect the blanks it is only necessary to displace them bodily in a plane normal to the plane of the face of the group of blanks. The interlocking projections may be made in various forms but I have shown them 55 dove-tailed because this will prevent disconnection of the blanks by movement in a direction lengthwise of the group, as well as by movement of separate blanks side-wise in the group and lengthwise of the blanks. It 60 is not new to provide a blank with edge projections but such blanks have been made heretofore, so far as I know, by stamping each blank singly from the end of a strip and without employing the projections to 65 make interlocking or interengaging connection between two or more blanks, and never before have these blanks been made with dove-tailed projections, so far as I am aware.

I do not limit myself as to the number or 70 as to the size of the blanks to be cut from a strip nor as to the exact form of the projections and I reserve the right to make all such changes as fairly fall within the 75 scope of the following claims.

I claim:

1. The herein described method of making printing plate blanks, which consists in cutting a strip along irregular lines to divide the strip into a plurality of blanks, the irregular lines of cut forming interlocking projections on the blanks to hold them in interlocking engagement as they are cut, moving the plurality of blanks bodily as a group from cutting position to distributing 90 position, and then separating the blanks.

2. A printing plate blank having a plurality of dove-tailed projections at opposite edges thereof and spaced apart between its ends.

3. A printing plate blank having a plurality of notches in opposite edges thereof forming dove-tailed projections.

4. A printing plate blank having a plurality of dove-tailed projections as thick as 100 the intermediate part of the blank and spaced apart between the ends of the blank.

5. A plurality of printing plate blanks arranged edge to edge, and projections at adjacent edges of the blanks spaced apart between the ends of the blanks and interlocking the blanks in strip formation against relative lateral movement.
6. A plurality of printing plate blanks

arranged edge to edge, and a plurality of dove-tailed projections at adjacent edges of the blanks interlockingly holding the blanks together in strip formation against relative movement laterally or longitudinally of the strip formation. 10

ROBERT C. ISAKSEN.
